UNITED STATES PATENT OFFICE.

RICHARD COOKE AND FLORUS J. COOKE, OF NEW HARTFORD, N. Y.

IMPROVEMENT IN STOPPING MECHANISMS FOR KNITTING-MACHINES.

Specification forming part of Letters Patent No. 151,374, dated August 25, 1874; application filed January 23, 1874.

To all whom it may concern:

Be it known that we, RICHARD COOKE and F. J. COOKE, of New Hartford, Oneida county, in the State of New York, have invented certain Improvements relating to Stop-Motions for Knitting-Machines, of which the following is a specification:

The object of the invention is to more rapidly and efficiently arrest the work and prevent the detachment of the web from the needles in case of the breakage of the yarn, or of the exhaustion of the yarn from the bobbin.

We provide a delicate feeler, which, while it offers no material resistance to the movement of the yarn, the moment the yarn ceases to support it, changes its position, and induces a prompt arrest of the action of the presser, (which, under ordinary conditions, liberates the stitches from the needles,) and thus leaves the old stitches fast on the needles until the machine stops, and a belt-shipper or other efficient means is operated at the same moment, so that the entire machine is stopped soon after. We provide also convenient means for setting the mechanism again in operation when the yarn has been again supplied. Two or more yarns are sometimes fed in simultaneously at different points. The usual practice, so far as our knowledge extends, is to thus supply four at once, at four equidistant points on the circle. We provide connections whereby the motion of the machine may be arrested from each and all of the yarn-feeding points by a single belt-shipper. We have succeeded, as the result of much reflection and many patient experiments, in attaining a high degree of perfection in the several combinations and details. Our improvements make it practicable to throw the presser out of action before the knitting has proceeded more than half-way around, even when the machine is running at its highest speed.

The following is a description of what we consider the best means of carrying out the invention.

The accompanying drawings form a part of this specification.

Figure 1 is an elevation of a portion, partly in section, in condition for working. Fig. 2 is a view at right angles, showing the novel parts as seen from the center of the knitting-ma-

chine, the needle-cylinder being removed. Fig. 3 shows one of the small parts detached, and Fig. 4 is a plan view of the several connections which lead from the several stop-motions to a single belt-shipper.

Similar letters of reference indicate corresponding parts wherever they occur.

A is the fixed frame-work of the machine. B is the needle-cylinder, a stout revolving ring which carries the needles b. The yarn is supplied to the needles with the proper amount of slack by the ordinary means, and the stitches are formed and liberated in the ordinary manner. M is the presser-wheel, which, while the yarn is supplied, performs the function of liberating the stitches by pressing against the elastic ends of the hooks, and allowing the stitches to slip freely up. There may be the usual stop-motion provided with a feeler, to detect the absence of a needle, or of any material part of a needle, and thus arrest the knitting and avoid mischief from such cause. Our invention has no relation to such stop, but is in nowise incompatible with its presence. It can work in combination with such other stop, and it will be usually desirable to so use it. We have not deemed it necessary to represent such other stop. We provide a delicate lever, C, having a loop or hook, C², embracing the yarn at one end, and formed into a spring-coil, C¹, at its opposite end. This coil C¹ embraces loosely a delicate horizontal shaft, D, which is provided with a projection, D¹, adapted to receive the abutting end of the spring-coil C¹. The other end of the shaft D is formed with a short arm, D², which acts under the delicate hooked pawl E, which, while the machine is running properly, keeps hold of the arm G² fixed on the upright shaft G, provided with a milled head or operating-button, G¹, mounted so as to be convenient of access above the presser M.

The button G¹ is milled around its edge, or otherwise adapted to be conveniently grasped by the thumb and finger of the attendant. Whenever the device, after having stopped the knitting-machine, is to be again adjusted for working, the button G¹ is grasped and turned by the attendant. This movement turns the arm G², and this acting on the pin J¹ turns the eccentric-wheel J back to its original

position, and allows the hook-pawl E to be again engaged, and all the parts are again in condition to allow the machine to run as before.

The shaft G is mounted in the axial line of the stud L¹, which supports the presser M, and around which it turns freely. The stud L¹ and the connected framing L² L³, which supports the entire delicate mechanism, are fixed on the slide L, which is supported in a long bearing in the fixed frame-work A, as shown, and is urged forward toward the revolving ring B by a spring, H, which may be made sufficiently powerful to exert considerable force. On the back end of the slide L is a shoulder, L⁴, which, whenever the slide L and its connections are moved backward by any force, receives a stout spring-pawl, I, and is retained.

J is a horizontal wheel, faced on its periphery with leather or rubber, j, and mounted eccentrically on a stud, l, which is fast on the framing L³. A spring, K, preferably concealed within or under the wheel J, exerts a constant but gentle force, tending to turn the eccentric-wheel J, and bring its soft frictional surface j into contact with the revolving ring B. When this motion is permitted, its friction against the ring B is sufficient to induce its being turned rapidly into a position where its full side will be toward the ring B, and, consequently, the stud L¹ and the entire slide L and its connections will be instantly moved backward against the force of the spring H.

The eccentric-wheel J has a pin, J¹, on its upper surface, which, when the knitting-machine is working successfully, presses against the arm G², and is retained thereby, so that the eccentric J presents its lean side toward the revolving ring B, and is therefore out of contact therewith; but if, by any means, the horizontal shaft D shall be turned so as by its arm D² to lift the hooked pawl E, then the arm G² yields to the slight but constant pressure received from the spring K, through the pin J¹, and turns, thereby liberating the wheel J, which instantly turns into such position that its frictional surface is acted upon by the rapidly-revolving ring B, with the inevitable result of instantly throwing the entire slide L, with its attachments, including the presser M, away from the ring B, and thus the further action of the presser M against the needles b is instantly arrested. The link T leads from one part of the slide L, or its attachments, to a suitable connection to operate the belt-shipper, so that the entire machine soon stops, and the work is suspended, with the stitches still fast upon the needles, until the attendant can restore the yarn and again put the machine in condition for operating. This turning of the delicate shaft D is effected the moment the yarn ceases to support the still more delicate lever C. The falling of the latter acts, through its spring end C¹, to cause a slight rotation of the shaft D.

Lest this may not be sufficient to liberate

the hooked pawl E, we provide a tumbling-bob, P, which is adjustable on the shaft D by means of the pinching-screw p. The bob P should be carefully adjusted on the shaft D, so as to be in a nearly perpendicular position when the knitting is progressing successfully. When the long slender lever C falls by the breaking of the yarn it gives a sufficient rotation to the shaft D to throw the gravity of the bob P on the other side of the central line. In this position its gravity aids the further rotation of the shaft D, and insures that the hooked pawl E will be promptly lifted.

The yarn is supported at two points close to the loop C², one in passing through the guide a¹ attached to an arm, a, on the fixed framing A, and another by the wire a², which extends out horizontally from the arm a, and is bent down at its outer end, as shown. A slight strip of india-rubber, f, extends from the bent-down end of the wire a² to the arm a. In its ordinary position the lever C, while the machine is working, presses gently upward against this rubber string, which thus serves as a spring. When the yarn fails to support the lever C it falls the more rapidly in consequence of the slight impulse it receives from the spring f. This spring may be of metal or other material, if preferred.

We have not deemed it necessary to represent the belt-shipper; but Q is the slide, which may be understood as operating it. R¹, R², and R³ are levers turning on their respective centers r, and operated, respectively, by the links T¹ T² T³, and connecting them to three other slides corresponding to the slide L, and supporting pressers corresponding to the presser M. When either of the yarns fails the corresponding links T T¹ T² T³ move the slide Q with the effect of arresting the entire machine. As soon as practicable during the period that the motion of the machine is being arrested the respective presser is thrown out of action, so that the work shall not be thereby disengaged from the needles.

The wheel J may operate with some success without the rubber or other soft periphery, j. It is only important that it shall take such a hold of the ring B that it will be turned thereby. The apparatus may be worked with some success without employing the wheel J, and by simply applying the spring K, or an equivalent spring, to the upright shaft G. In such case the arm G² may be made of such length as to come directly in contact with the stout revolving ring B, and be operated thereby, so as to throw the slide L and its connections back by the force thus received. This action may be made more perfect by forming the end of the arm G² in a segment of a circle, or ellipse. In such case we would prefer to face its outer edge with a coating of rubber.

There may be many modifications of some of the details. If, for example, it should be desired to lift the presser M, so as to carry it above the needle, instead of pushing it horizontally away, the upper face of the wheel J,

or of the arm G^2 , may carry a cam, which may act on a slide properly mounted, to be lifted by the cam, and thus to throw the presser out of work whenever the lever C is dropped.

We claim as our invention—

1. The feeler C , liberating-catch E , and the spring K , combined, as shown, with a constantly-moving portion, B , and with an intermediate piece, J , or its equivalent, so that, on the failure of the yarn to support the feeler C , the moving part B shall remove the presser M and prevent the further detaching of the stitches, as herein set forth.

2. In a knitting stop-motion substantially of the character described, the shaft D and tumbling-bob P , in combination with the feeler C and liberating-catch E , as herein specified.

3. The combination of the shaft D , provided with the stop D^1 , and the feeler C C^1 , forming a loose joint between the two, and allowing the shaft D to turn farther than the feeler C , as and for the purposes specified.

4. The spring f , in combination with the

feeler C and its connections, serving to induce a more rapid movement of the feeler when the yarn fails to support it.

5. The button G^1 , or its equivalent, on the shaft G , in combination with the presser M , means for throwing it out of contact with the needles, and with the arm G^2 and its connections, for again setting the parts in condition for working; as herein specified.

6. The several connections T T^1 T^2 , &c., and levers R^1 R^2 , &c., communicating motion from the several distinct yarn-supplying mechanisms to a single belt-shipper for arresting the entire machine, as herein specified.

In testimony whereof we have hereunto set our hands this 21st day of January, 1874, in the presence of two subscribing witnesses.
